(57) **CLAIM**

The ornamental design for a phone wallet with finger-slide, as shown and described.

DESCRIPTION

FIG. 1 is a top, facing, right perspective view of our new design for a phone wallet with finger-slide;

FIG. 2 is a rear, bottom, left perspective view thereof;

FIG. 3 is an elevated facing view thereof;

FIG. 4 is an elevated rear view thereof;

FIG. 5 is a top, plan view thereof;

FIG. 6 is a bottom, plan view thereof;

FIG. 7 is an elevated right side view thereof; and

FIG. 8 is an elevated left side view thereof.

FIG. 9 is a top, facing, right perspective view of another configuration of our new design for a phone wallet with finger-slide;

FIG. 10 is a rear, bottom, left perspective view thereof;

FIG. 11 is an elevated facing view thereof;

FIG. 12 is an elevated rear view thereof;

FIG. 13 is a top, plan view thereof;

FIG. 14 is a bottom, plan view thereof;

FIG. 15 is an elevated right side view thereof; and

FIG. 16 is an elevated left side view thereof.

FIG. 17 is a top, facing, right perspective view of another configuration of our new design for a phone wallet with finger-slide;

FIG. 18 is a rear, bottom, left perspective view thereof;

FIG. 19 is an elevated facing view thereof;

FIG. 20 is an elevated rear view thereof;

FIG. 21 is a top, plan view thereof;

FIG. 22 is a bottom, plan view thereof;

FIG. 23 is an elevated right side view thereof; and,

FIG. 24 is an elevated left side view thereof.

Dashed lines of equal length on the facing and rear surfaces represent claimed stitching. Alternating long and short dashes along the side edges and the lower square portion shown on the front and side views indicate unclaimed subject matter.

1 Claim, 15 Drawing Sheets
